**COMBINED VALVE ACTUATOR AND DISPENSER
FOR A PRESSURIZED CONTAINER**

Vassiliou Milcos, Suffern, N.Y., assignor to
Avon Products, Inc.

Filed Dec. 5, 1969, Ser. No. 20,384

Term of patent 14 years

Int. Cl. D9—99

U.S. Cl. D9—258

FIG. 1.

FIG. 2.

FIG. 3.

FIG. 4.

FIG. 5.

FIG. 1 is a perspective view of a combined actuator and dispenser for a pressurized container showing my new design;

FIG. 2 is a top plan view;

FIG. 3 is a front elevational view;

FIG. 4 is a side elevational view; and

FIG. 5 is a bottom plan view.

I claim:

The ornamental design for a combined valve actuator and dispenser for a pressurized container, as shown.
